Attorneys.

UNITED STATES PATENT OFFICE.

CHARLES H. BENCKENSTEIN, OF VINTON, LOUISIANA.

TUBING SPIDER.

Application filed March 18, 1922. Serial No. 544,903.

To all whom it may concern:

Be it known that I, CHARLES H. BENCKENSTEIN, a citizen of the United States, residing at Vinton, in the parish of Calcasieu and State of Louisiana, have invented certain new and useful Improvements in Tubing Spiders, of which the following is a full, clear, and exact description.

My invention relates to tubing spiders, and one of the particular applications of the invention is in connection with the lowering of pipe, tubing or casing into a well, and the removal of the same from a well; though it will be obvious from the description hereinafter that the invention is equally well adapted to the raising and lowering of any similar structure.

Heretofore much time and labor have been required for the operation of lowering and raising pipe, tubing, casing, etc., in a well, and one of the objects of my invention is to greatly reduce the time and labor heretofore involved in this operation.

Another object of my invention is to provide an apparatus of this character which will permit tighter joints to be made between the pipe connections than has been possible with previously known apparatus.

A further object of my invention resides in the provision of a tubing spider so constructed on the interior as to prevent any catching or hanging up of the pipe collars while passing through the apparatus.

Still another object of my invention is to provide an apparatus of this character which is formed of two parts, whereby it may be quickly and easily mounted or dismounted.

Another advantage of my invention resides in the provision of a mechanism for positively controlling the movements of the rocking arm and sliding jaw in proper sequence.

A further advantage of my invention, and one which is a very material feature thereof, resides in the provision of a special operating mechanism including a locking feature, whereby the rocking arm and sliding jaw are positively locked in the cylindrical passage and can be removed therefrom only by the proper operation of the operating mechanism.

Other and further objects of my invention will appear as the description proceeds.

The common practice has formerly been to raise and lower pipe in a well by means of "elevators." One "elevator" would be attached around the pipe below the collar thereof, and the pipe would then be pulled out to the desired height by a derrick. After pulling one or more sections from the hole, a second "elevator" would be attached around the bottom collar of the pipe, and the pipe then let down onto this second "elevator." The pipe would then be disjoined and removed, and the operation would be repeated. In lowering pipe into the well the operation was much the reverse to that of taking it out.

In some instances, instead of using an "elevator" to hold the pipe left standing in the well, corrugated wedges were placed between the pipe and the casing.

My invention takes the place of the holding "elevator," or the holding wedges, and by the substitution of my invention, not only is much time and labor saved, but also the operation is performed in a much more satisfactory manner.

The present invention constitutes an improvement on tubing spiders invented by me and forming the subject-matter of application No. 454,445, filed March 22, 1921, and application No. 510,011, filed October 24, 1921.

One of the important improvements incorporated in the present invention consists in providing a special operating mechanism whereby the rocking arm and sliding jaw are automatically and positively locked in the cylindrical passage, and cannot be accidentally displaced therefrom.

I will now proceed to describe one particular form of my invention, it being understood that those skilled in the art may make many changes and modifications therein without departing from the spirit of my invention as defined in the appended claims; and the drawings forming a part of this application are, therefore, to be considered merely as illustrative and not in any limiting sense.

In the drawings:

Figure 1 is a side elevation of the complete mechanism, parts thereof being in section, and parts being broken away.

Figure 2 is a plan view of the complete mechanism, a section of tubing being shown as gripped by the apparatus, and

Figure 3 is a fragmentary plan view of the sliding jaw and inclined face of the rocking member.

Referring to the drawings more in detail, 5 the apparatus is preferably formed of two sections indicated by numerals 1 and 2, and these sections are shown as hingedly connected by means of links 3.

A semi-cylindrical passage is formed in 10 each of the sections, so that when the apparatus is closed there is a cylindrical passage 4 extending vertically therethrough. The passage is flared at its top and bottom, as indicated by numerals 5 and 6.

15 A plate 7 having gripping teeth 8 thereon is mounted in one of the wall sections, the curvature of the gripping teeth being substantially the same as the curvature of the pipe to be handled. It will be obvious 20 that, instead of mounting the toothed plate in one of the sections, I may prefer to form the teeth in the walls of both sections, so that when the sections are closed a gripping surface similar to the one just described will 25 be presented.

Oppositely arranged with respect to the above described gripping teeth is a rocking arm 9, pivotally mounted in the body of the spider, as will be described herewith. The 30 rocking arm 9 has an inclined face 10 on which is slidably mounted a gripping jaw 11. The particular manner in which the jaw is slidably mounted on the inclined face constitutes no part of the present invention; 35 but in the particular construction illustrated the rear of the jaw is provided with portions 12 overlapping flanges 13 on the rocking arm; and also with a center tongue 14 engaging a groove 15 in the inclined face 40 of the rocking member. A pin 16 (Fig. 3) is employed to engage the center tongue and thus limit the upward or outward movement of the sliding jaw; the downward or inward movement of the same being limited by the 45 engagement of the jaw with the flange 17 of the rocking member.

The face of the sliding jaw is concave, and is provided with gripping teeth or 50 ridges 18, the curvature thereof being substantially the same as the curvature of the pipe or tubing to be handled. As shown in the drawings, the teeth in the body of the apparatus and also those on the face of the jaw are arranged to act upwardly.

55 The rocking member 9 is provided with journal bearings 19 and 20, the journal 19 being secured to the section 2 by means of a collar 21, so that the rocking member will remain in position when the sections 1 and 60 2 are separated. The section 1 is, of course, recessed for the purpose of receiving the journal bearing 20 when the sections are closed.

65 A stirrup 22 is slidably positioned in the rocking member just behind the sliding jaw,

the stirrup being provided with an inwardly projecting portion 23 for engaging the sliding jaw. A bell-crank lever 24 is shown as having a bearing in section 2, and the other section is cut away, as indicated by numeral 25, so that the operating mechanism does not prevent the closing of the sections. A link 26 connects the stirrup with one arm of the bell-crank lever.

The operation of the mechanism thus far 75 described is as follows:

As the stirrup is raised it lifts the sliding jaw until the jaw has traveled the full extent of its upward movement, after which the continued movement of the bell-crank 80 lever causes the rocking arm to be thrown backward. In throwing the rocking arm and sliding jaw into operative position, the action is just the reverse, the rocking arm being first thrown to the left, and thereafter 85 a continued movement of the bell-crank lever permits the sliding jaw to slide downwardly into engagement with the pipe. The parts are thus caused to move in proper sequence, and this is of great importance 90 because by such an arrangement the sliding jaw is positively maintained in its elevated position until after the rocking arm is in its operative position.

If desired, springs could be employed for 95 normally holding the sliding jaw in its elevated position. Such springs are illustrated in my application Serial No. 454,445 previously referred to.

For the purpose of securely locking the 100 two sections in closed position, I provide a bolt 27 which is preferably pivotally mounted in one of the sections and engaging a groove in the other section. A nut 28 screw threaded on the bolt 27 engages the wall of 105 section 1 and draws the two sections firmly together.

Numeral 29 indicates a section of pipe or 110 tubing gripped by the apparatus.

I will now describe the locking feature of 110 the mechanism, which feature is the material improvement of the present invention over the prior construction illustrated and described in my previous applications Serial No. 454,445 and Serial No. 510,011.

The purpose of the locking feature is to 115 prevent the rocking arm and the sliding jaw carried thereby from being accidentally thrown from their operative position in the cylindrical passage. For example, suppose 120 a section of pipe is being lowered into the cylindrical passage, the collar of the pipe being held some distance above the device by "elevators," and one of the crew carelessly disjoins the "elevators" and allows the pipe to fall into or through the device. If 125 the teeth or ridges 18 on the sliding jaw are somewhat dull, the pipe may slip through the cylindrical passage, and the collar attached to the pipe section dropping 130

heavily on the sliding jaw may thereby cause it to rebound with the rocking arm and come out of the cylindrical passage, thus permitting the pipe to fall into the well. It is thus obvious that it is highly desirable to provide some simple and automatic means whereby the rocking arm is positively locked in the cylindrical passage against accidental displacement.

10. The means which I have invented for producing this highly desirable result consists of providing a notch 30 in the journal 19 of the rocking member 9, and in the collar 21, and in so arranging the operating levers 15 that the end of the lower arm of bell-crank lever 24 will be received in the notch 30 when the rocking arm is moved to its operative position in the cylindrical passage.

It will be apparent from an inspection 20 of the drawings that any shocks transmitted to the device cannot accidentally displace the rocking arm, because as soon as the rocking arm starts to move the wall of the notch 30 will engage the end of the bell-crank and 25 the motion will be stopped.

Any suitable means may be employed to 30 operate the bell-crank lever to throw the sliding jaw and rocking arm out of the cylindrical passage. In the specific embodiment illustrated I employ a depending link 31 pivotally attached at its upper end to the lower arm of the bell-crank lever, and at its lower end it is pivotally attached to the lever 32 mounted in the bracket 33. 35 The lever may be operated by hand or foot. A spring 34 normally holds the various parts in the positions indicated on the drawings.

In using my invention, the operation of 40 removing pipe from a well is as follows:

Assuming the spider to be mounted in 45 position and the rocking arm and sliding jaw thrown out of the cylindrical passage, then the pipe is freely withdrawn through the cylindrical passage until one or more 50 sections of the pipe are clear; any desired means, such as a derrick and "elevator" being employed to hoist the pipe. After the pipe has been elevated to the height desired, 55 the rocking arm is thrown down into operative position. When this is done, the concave toothed surface of the sliding jaw engages and forces the pipe over into engagement with the toothed surface 8 provided in the wall of the passage. The downward pulling force exerted by the pipe causes the jaw 11 to slide down the inclined face of the rocking arm, with a resulting wedging action, which causes both sets of 60 teeth to bite into the pipe and hold it securely without any liability of dropping.

The pipe sections are now disjointed and moved to one side.

The "elevator" or any other hoisting 65 means is now connected to the top section

remaining; the rocking arm and sliding jaw are thrown back, thereby releasing the pipe; which is now hoisted to the desired extent, and the operation previously described is repeated.

The operation of lowering pipe or tubing is practically the reverse of the operation of removing the same, and a description thereof is thought to be unnecessary.

So far as the present invention is concerned, the body of the spider may be made in one piece or two pieces; but for reasons given in my application Serial No. 510,011 it is highly desirable that the body of the spider be made in two pieces whereby it 80 can be clamped into place quickly and easily.

It is to be noted that by having the passage 4 flared at both bottom and top it is impossible for the couplings to be caught, 85 and when the gripping mechanism is thrown back the passage is entirely clear, so that the pipe and couplings may pass therethrough clearly, and without any liability of the pipe being hung up either in lowering or raising it.

It is also to be particularly noted that by the use of the novel locking feature described herein there is no danger of pipe being dropped into the well because of the 95 rocking arm being accidentally displaced as the result of shocks or otherwise.

In accordance with the patent statutes, I have described what I now believe to be the best embodiment of my invention, but 100 I do not wish to be understood thereby as limiting myself or the scope of my invention, as many modifications may be made without departing from the spirit of my invention, and all such I aim to include in 105 the scope of the appended claims.

What I claim as new and desire to secure by Letters Patent is:

1. A spider including a body member provided with a passage extending therethrough, an arm journaled in the body to swing in a vertical plane and adapted to project into the passage, and means cooperating with the journal for positively locking said arm against accidental displacement 110 from said passage.

2. A piping spider composed of two sections, means for securing the two sections together, the two sections being so arranged as to form a substantially cylindrical passage 115 therethrough when the two sections are together, a rocking arm journaled in one of the sections and adapted to project into said passage, and means cooperating with the journal for positively locking said arm 120 against accidental displacement from said passage.

3. A tubing spider including a body member provided with a passage extending therethrough, an arm journaled in the body 125

- member to swing in a vertical plane and adapted to project into the passage, means for normally operating said arm, and means cooperating with the journal for positively locking said arm against accidental displacement from said passage.
4. A spider including a body member provided with a passage extending therethrough, an arm pivotally mounted in the body member and adapted to project into said passage, the pivotally mounted arm being provided with a notch, and means engaging said notch and preventing accidental movement of said arm.
- 15 5. A piping spider including a body member provided with a passage therethrough, an arm pivotally mounted in the body member and adapted to project into said passage, a bell-crank lever for normally operating the rocking arm, the pivotally mounted arm being provided with a notch, and one arm of said bell-crank lever adapted to engage said notch when the pivotally mounted arm is in operative position in the passage.
- 25 6. A tubing spider having a passage extending therethrough, a rocking arm adapted to be projected into the passage, a gripping jaw slidably mounted on the rocking arm, operating means associated with the sliding jaw to cause said jaw and rocking arm to move in proper sequence, the rocking arm being provided with a notch, and said operating means engaging said notch when the rocking arm is in operative position, whereby accidental displacement of the rocking arm is prevented.
- 30 7. A spider having a passage therethrough, a rocking arm adapted to be projected into said passage, a gripping jaw slidably mounted on said arm, means for

limiting the movement of the sliding gripping jaw, a stirrup arranged to engage and lift the sliding jaw, a bell-crank lever, a link connecting one arm of the bell-crank lever with the stirrup, the rocking arm being provided with a notch, and one arm of the bell-crank lever adapted to engage said notch when the rocking arm is in operative position.

8. A piping spider composed of two sections, means for securing the two sections together, the two sections being so arranged as to form a substantially cylindrical passage therethrough when the two sections are together, a rocking arm having journals mounted in said sections, a collar securing one of the rocking arm journals to one of the sections, said journal and collar being provided with a notch, and means adapted to engage said notch and prevent accidental displacement of the rocking arm from the cylindrical passage.

9. A tubing spider including a body member having a passage extending therethrough, a rocking arm adapted to be projected into the passage, said rocking arm having a journal mounted in the body member, a gripping jaw slidably mounted on the rocking arm, a stirrup adapted to engage said gripping jaw, a bell-crank lever, one arm of the bell-crank lever being operatively connected with the stirrup, the journal of the rocking arm being provided with a notch, the other arm of said bell-crank lever adapted to engage said notch when the rocking arm is in operative position, and a link and lever mechanism for operating the bell-crank lever.

CHARLES H. BENCKENSTEIN.
